TROPHY BASE

Alfred John Flauder, Trumbull, Conn., assignor to Alexander M. Pistey, Bridgeport, Conn.

Application December 22, 1955, Serial No. 39,445

Term of patent 7 years

(Cl. D29—23)

Fig. 1

Fig. 2

Fig. 1 is a front elevational view of a trophy base, showing my new design, the rear elevation view being the same;

Fig. 2 is an end elevational view thereof, the opposite end view being the same; and

Fig. 3 is a top plan view thereof.

I claim:

The ornamental design for a trophy base, as shown.
